CLAIM

The ornamental design for a lid for a container, as shown and described.

DESCRIPTION

FIG. 1 is a front, top, right perspective view of a lid for a container showing my new design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The broken lines in the Figures are for the purpose of illustrating portions of the lid for a container and form no part of the claimed design.
